UNITED STATES PATENT OFFICE.

AXEL S. VOGT, OF ALTOONA, PENNSYLVANIA.

LOCOMOTIVE-BLOWER.

1,285,484.

Specification of Letters Patent. Patented Nov. 19, 1918.

Application filed April 3, 1917. Serial No. 159,527.

To all whom it may concern:

Be it known that I, AXEL SAMUEL VOGT, a subject of the King of Sweden, residing at Altoona, in the county of Blair and State of Pennsylvania, have invented certain new and useful Improvements in Locomotive-Blowers, of which the following is a specification.

This invention relates to an improvement in blower devices for steam locomotives wherein a forced draft is necessary to carry off the products of combustion.

To this end it is proposed to provide a novel blower device which may be conveniently carried by the lower end of the lift pipe and located at the proper distance above the exhaust pipe to obtain the desired results. In this latter connection it is proposed to provide a device which may be entirely independent of the exhaust pipe for support, and of such a construction that the steam jet openings thereof will not become stopped or clogged by oil from the locomotive cylinders which usually hardens or solidifies at or about such openings and interferes with the proper performance of the blower.

A further object of the invention is to provide a blower device of such a character that it may be readily secured to the lower end of the lift pipe from the outside thereof through the use of suitable fastening devices, thus greatly facilitating the installation of the device and its removal in case of necessity.

Another object of the invention is to provide a blower device in the form of a ring-like casting wherein the steam jet orifices have a novel disposition with regard to the lift pipe, whereby steam discharged therefrom will effectively sweep the lift pipe of the air and gases contained therein to thereby create a partial vacuum in the smoke box which the air beneath the grate, and products of combustion will seek to fill, thus causing the proper draft for the locomotive.

With these and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a plan view of the improved blower casting.

Fig. 2 is a vertical sectional view taken on the line 2—2 of Fig. 1.

Fig. 3 is a longitudinal sectional view of a locomotive smoke box showing the blower device fitted to the lower end of the lift pipe.

Fig. 4 is a transverse sectional view of the construction shown in Fig. 3, showing more clearly the relation of the blower device to the usual form of exhaust pipe.

Figs. 5 and 6 are respectively longitudinal and transverse sectional views showing the blower device installed in a smoke box wherein the lift pipe is formed in sections.

Similar references designate corresponding parts throughout the several figures of the drawings.

Heretofore it has been customarily the practice to secure the blower casting to the exhaust pipe by suitable fastening means or locate the same in such a position with reference thereto that the oil from the locomotive cylinders carried out through the said pipe has an opportunity to solidify or harden around the jet orifices to such an extent that it often closes such openings or at least reduces their diameter to such an extent that the efficiency of the blower is greatly reduced.

Accordingly, the present invention aims to eliminate this objection by suspending the blower device a suitable distance above the exhaust pipe and also arranging the jet orifices in such a manner that the possibility of oil collecting thereabout is reduced to a minimum, thus keeping the blower in a proper state of efficiency. In carrying this idea into effect no change or alteration is contemplated in the usual smoke box construction, nor in the design of the exhaust pipe or smoke stack. That is to say, the present improvement is particularly directed to a novel blower device which is preferably in the form of a ring-like casting, designated in the drawings generally as 10 and having formed at one end thereof a suitable attaching flange 10^a which is adapted to receive therein the lower end of the lift pipe 11, in such a manner that the blower and pipe may be readily secured together by means of suitable fastening bolts 12. As will be observed from the drawings these bolts are arranged in such a manner that the nuts thereof may be placed thereon from the exterior of the pipe and blower device, thus facilitating the securing of the latter to the lift pipe. And, as will also be observed from the drawings, in order to assist in properly fitting the blower device to the end of the

lift pipe, the same is preferably provided with an interior annular shoulder 13 for abutting against the lower edge of the lift pipe.

- 5 From the foregoing it will be apparent that the upper end of the blower ring is adapted to be fitted to the lift pipe and held at a fixed distance above the discharge end of the exhaust pipe, and with further reference to the features and characteristics of the device it may be noted that the lower end 15 thereof is outwardly flared, or of bell-shaped formation, whereby the products of combustion in the smoke box will be assisted 10 into the lift pipe, as well as the steam from the exhaust pipe, whereby they may readily make their exit through the usual smoke stack 16.

The intermediate or body portion of the blower ring 10 is formed with an annular steam channel 17 which is preferably located on the exterior surface of the ring, and also includes a plurality of inwardly projecting nozzle portions 18, each of which has an 20 upper inclined face 18^a disposed obliquely to the plane of the shoulder 13 and is provided in such face with a jet orifice 19 whose axis is disposed obliquely to the axis of the lift pipe and blower ring.

30 It will be obvious that the novel formation of these nozzle portions 18 prevents the accumulation of oil and the like. That is to say, owing to the inclination of the face 18^a all liquids will drain rapidly therefrom, and 35 materially assist in the cleaning action produced by the steam issuing from the jet orifices 19. As there is a plurality of these jet orifices 19 disposed in the manner indicated around the interior of the blower ring, it will 40 be apparent that the steam jets issuing therefrom will converge to a point as indicated by the arrows in Fig. 3, thus providing in effect a conical steam spray which will effectively create an up-draft in the lift pipe 11.

45 For the purpose of supplying necessary steam to the passage 17, the same is provided at a suitable point with a securing flange 21 which is adapted to have fitted thereto the corresponding flange 22 of a coupling associated with the steam supply pipe 23 shown 50 in Fig. 3 of the drawings.

In the form of the invention shown in Figs. 1 to 4 inclusive it will be observed that the lift pipe 11 having the novel blower device 10 fitted to its lower end is of one piece and is connected directly with the smoke stack 16. Also as shown, this blower ring is suspended a suitable distance above the exhaust pipe 25 to properly receive the exhaust 55 steam therefrom and because of its one-piece characteristic above pointed out, constitutes the only outlet from the smoke box. Thus, in this form of the invention all of the smoke, gases and other products of combustion 60 as well as the steam from the exhaust 65

pipe 25 must pass through the bell-mouthed portion 15 of the blower ring and thence through the lift pipe 11 to the stack 16, which has the advantage of providing a more effective draft, since the full force of 70 the steam issuing from the exhaust nozzle 25 as well as from the jet orifices 19 is concentrated in the lower end of the lift pipe and has the effect of an ejector for all of the products of combustion in the smoke box. 75 In this form a true forced draft is obtained, there being no provision for any of the products of combustion to escape from the smoke box under natural draft since the smoke pipe 11 is in effect a continuation of the stack 16, 80 and the only outlet is through the bell portion 15 which is located well down in the smoke box.

In the form of the invention shown in Figs. 5 and 6 the same type of blower ring 85 may be utilized as shown in Figs. 1 to 4 inclusive. However, in these figures the blower ring is shown in connection with a lift pipe which is made in sections instead of one piece as in Figs. 1 to 4. Thus in 90 this form of the invention the lift pipe 11^a consists of a tubular section *b* of uniform diameter throughout and an upper section *c* of tapering cross section, said latter section *c* being spaced from the upper end of the section *b*, thus providing three points of outlet for the gases from the smoke box, namely at the points *x*, *y* and *z* instead of one as in Figs. 1 to 4. In this form the products of combustion may escape from the smoke box 95 to the stack 16 by natural draft through the passages indicated as well as with the assistance of the blower device.

Although in the form of the invention shown in Figs. 5 and 6 a different type of 105 lift pipe is shown, the functions of the blower device 10 nevertheless remain the same.

Without further description it is thought that the invention will be readily understood by those familiar with the art and it will of course be understood that minor changes in the form, proportion and details of construction may be resorted to without departing from the spirit of the invention or 110 the scope of the appended claims:

1. A blower unit adapted to be suspended from the inner end of smoke-stack extensions of steam locomotives consisting of a ring-like body having a flared open mouth 115 at one side and a relatively restricted stack receiving and bolting flange at the other, an annular abutment shoulder on the inner face of the body for engaging with the end of the stack extension embraced by said flange, 120 an intermediate steam conducting passage formed on the outer face of the ring body, and a plurality of inwardly projecting nozzle elements in communication with said passage and each having an upwardly 125 130

directed and obliquely inclined jet orifice located adjacent the abutment shoulder.

2. A blower unit adapted to be suspended from the stack extension of steam locomotives including an integral bell mouthed ring shaped body casting having a smoke-stack extension-receiving flange and an abutment shoulder at one end, and an internally cored steam passage formed with a

plurality of interiorly offset nozzle portions 10 located adjacent and below said abutment shoulder.

In testimony whereof I affix my signature in presence of two witnesses.

AXEL S. VOGT.
